(57) **CLAIM**

The ornamental design for a protective food storage container, as shown and described.

DESCRIPTION

This application is related to commonly owned, concurrently filed U.S. Utility patent application Ser. No. 10/097, 311 filed Mar. 14, 2002, entitled Protective Food Storage Container.

FIG. 1 is a perspective view of a protective food storage container showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a cross-section view thereof taken along line 6—6 of FIG. 2;

FIG. 7 is a top plan view thereof; and,

FIG. 8 is a bottom plan view thereof.

The broken lines are for illustrative purposes only and form no part of the claimed design.
